Primary Examiner — Elizabeth Albert(74) *Attorney, Agent, or Firm* — Plumsea Law Group, LLC(57) **CLAIM**

The ornamental design for a stand, as shown and described.

DESCRIPTION

FIG. 1 is a top perspective view of a stand showing the new design;

FIG. 2 is a front side elevational view of the stand of FIG. 1; FIG. 3 is a rear side elevational view of the stand of FIG. 1; FIG. 4 is a right side elevational view of the stand of FIG. 1; FIG. 5 is a left side elevational view of the stand of FIG. 1; FIG. 6 is a top plan view of the stand of FIG. 1;

FIG. 7 is a bottom plan view of the stand of FIG. 1; and,

FIG. 8 is a top perspective view of the stand of FIG. 1.

The evenly spaced broken lines showing portions of the stand in FIGS. 1-8 are included to show features that form no part of the claimed design.

The long and short broken lines in FIGS. 1-6 and 8 that define the bounds of the claimed design form no part thereof.
